PLURAL WIRE STRIPPER AND ELECTRICAL CONNECTOR

Albert S. Gibson, Detroit, Mich., assignor of one-half to Warren H. Kintzinger, Dearborn, Mich.

Application October 4, 1951, Serial No. 249,766

7 Claims. (Cl. 339—98)

This invention relates to improvements in electrical wire connectors and more particularly to connectors for firmly joining a plurality of insulated wires together in physical and electrical contact and without the necessity of removing the insulation from the wires.

An important object of the invention is to provide a connector for electrical wires, and particularly for wires having insulated coverings, which is designed in a novel manner to effect the connection between all of the wires by movement of a single member in the connector. Another important object of the invention is to provide a connector for this purpose having means for cutting through the insulation of the wires and for firmly gripping the wires to form a strong anchor for the wires. A further important object of the invention is to provide a connector of this character which is simple in construction and use, is inexpensive to manufacture and assemble, and results in a connection which is substantially moisture-proof and as strong as the wires themselves.

In carrying out the objects of the invention, the connector comprises a housing or block of insulating material in which substantially parallel extending channels are formed for receiving insulated covered wires. Movably mounted in the housing or block is an electrical contact member in the form of a perforated plate arranged in a plane substantially perpendicular to the axes of the channels and so as to intersect the channels. The perforations of the plate member are arranged in a pattern like that of the channels for registration or alignment therewith. Each perforation is elongated in one dimension and widened at one end sufficient to receive both the wire and its insulating covering and narrowed at the other end sufficient to receive only the wire itself. The plate member is movably mounted in the housing in its plane from one position in which the widened sections of the perforations align with the channels to another position in which the narrowed sections of the perforations align with the channels, the arrangement and location of the sections of the perforations to the channels being such that during this movement the side walls of the narrowed sections of the perforations cut through or penetrate the insulating covering for direct electrical contact with the wires. In this preferred arrangement, the plate member is thus constructed to effectually grip the wires and to penetrate the insulating covering material thereof to form a positive electrical connection with the wires.

An important feature of the invention is the provision for controlling the movement of the plate member from the outside of the housing. This is accomplished as herein disclosed by projecting the plate member through and beyond one side of the housing to provide an extension for actuating the member. Carried by the extension of the plate member is a body of insulating material which is arranged for abutment with the side of the housing through which it projects when the movement of the member is completed. The result is that when the operation is concluded the plate member and its electrical con-

2

nection to the wires is wholly enclosed within insulating material and effectively protected from dirt, moisture and other foreign matter.

Various other objects, advantages and meritorious features will become more fully apparent from the following specification, appended claims and accompanying drawings wherein:

Fig. 1 is a perspective view of one form of connector constructed in accordance with this invention and showing a plurality of wires entering the connector and the final position of the parts of the connector.

Fig. 2 is a longitudinal vertical sectional view taken along line 2—2 of Fig. 1 and showing movable plate member in its final wire gripping position.

Fig. 3 is a longitudinal sectional view similar to Fig. 2 but showing the plate member in its initial position.

Fig. 4 is a horizontal sectional view taken along line 4—4 of Fig. 3.

Fig. 5 is a horizontal sectional view taken along line 5—5 of Fig. 2.

Fig. 6 is an enlarged fragmentary sectional view of one of the perforations of the plate member and showing the manner in which the perforation cuts through and removes portions of the insulating covering of a wire.

Fig. 7 is a sectional view taken along line 7—7 of Fig. 5 and showing a preferred arrangement for providing cutting teeth on opposite side wall portions of each perforation.

Fig. 8 is a sectional view taken along line 8—8 of Fig. 6 but in slightly reduced scale.

Fig. 9 is a top plane view of a modified form of connector, and

Fig. 10 is a vertical sectional view taken along line 10—10 of Fig. 9 and showing the internal construction of the modified form of connector.

Referring particularly to the drawing, the main body portion or housing of the connector is generally indicated at 10. As shown, the housing is preferably a rectangular shaped block of insulating material, such as plastic molded to the desired configuration. The block 10 is formed with a plurality of wire receiving openings or channels 12 which are arranged in spaced parallel relation to one another. All of these channels preferably open out through one side of the block, such as the upper face 14 thereof as shown in Fig. 1. Each channel is preferably circular in cross section and the diameter thereof is such as to slidably admit a given size of insulated wire.

Each wire receiving channel preferably extends to a depth in the block beyond the longitudinal medial line thereof. Depending upon the use intended for the connector, all of the channels may terminate short of the opposite or bottom side 16 of the block as shown by the embodiment of the invention illustrated in Fig. 10, or one or more of these channels may extend completely through the block and open out or through the bottom face of the block as well as the top face as shown by the embodiment illustrated in Figs. 1, 2 and 3. Thus one channel, such as that indicated at 18, is shown as extending completely through the block and opening out through both the top and bottom sides thereof.

Insulated wires entering certain of the channels of the block 10 are indicated at 20. The insulated covering for each wire is indicated by the reference character 22. One of these wires, such as that designated by the reference character 24, is received in the channel 18 which passes completely through the block. As shown in Figs. 1, 2 and 3, this wire not only enters the upper face of the block but projects from the lower face 16 thereof. This wire may lead to an electrical device for operating the same, such as an electric light fixture. The insulated wires 20 which are received in the shorter channels 12 are forced therewith until their inserted ends abut the bases or

closed ends of the channels in the manner shown in Figs. 2 and 3.

Received in the housing or block 10 is a movable member which is capable upon movement from one position to another position to not only tightly grip the wires received in the channels but also to cut through the insulation thereof and directly contact the wires therein. This member is in the form of a relatively thin flat plate 26 which may be of the rectangular formation shown in Figs. 4 and 5. This plate member is composed of electrical conductive material, such as copper, and is provided with a plurality of similarly formed perforations or holes arranged in a pattern similar to that of the channels 12 and 16. The housing or block 10 is provided with a relatively deep but narrow cavity 28 having substantially the same width and thickness of the plate 26 so as to slidably receive the same.

The cavity or recess 28 extends in a plane substantially perpendicular to the axes of the wire receiving channels and so as to intersect the same. As shown in Figs. 2 and 3 the cavity is preferably disposed on the longitudinal medial line of the block halfway between the upper face 14 and the lower face 18 thereof. It is evident that the perforated plate 26 is disposed by the cavity 28 in perpendicular intersecting relation to the channels and by virtue of having its perforations arranged in the same arrangement or pattern of the channels it is capable of being positioned in the cavity with its perforations in registration with the channels.

Referring particularly to Figs. 4, 5, 6 and 7, each perforation of the plate member 26 is elongated in one dimension and is provided at one end with a widened end section 30 and at the other end with a narrowed end section 32. The widened end section 30 of each perforation is preferably circularly formed as shown and having a diameter approximately equaling the diameter of the channels 12 and 16 so that the wires together with their respective insulating coverings may be easily passed therethrough. The narrowed end section 32 of each perforation is so dimensionally related to the insulated wires for which the connector is intended that upon relative movement of a wire thereto, the opposite side walls of the narrowed section will cut through the insulating covering and directly contact the exposed portions of the wire. Although the opposite side walls of the narrowed sections 32 may extend parallel to one another to accomplish this purpose, they are preferably arranged in slightly diverging relationship as best shown in Fig. 6. The opposite side walls of the narrowed end section 32 of each perforation are indicated by the reference character 34-34. These side walls open into the circular widened end section 30 in a slightly diverging or outwardly flaring relationship to one another. As an insulated wire is forced into the narrow section 32 of a plate perforation, the opposite side walls 34-34 thereof cut through the insulating covering forcing the dislodged insulating material into the circular widened section 30 as shown at 36 in Fig. 6. When the relative movement of the wire and plate is completed, the opposed side walls 34-34 come into contact with the wire 20 forming an electrical connection between the wire and the plate.

In addition to tapering or flaring the side walls 34-34 of each perforation relative to one another to effect the cutting operation, it is also desired to incline or bevel the side walls in the manner shown in Fig. 7. So inclined, the side walls provide a pair of oppositely positioned cutting edges at the entrance of the reduced end section 32 of each perforation. Such cutting edges are referred to by the reference characters 38-38 in Figs. 6 and 7. As the insulated wire is advanced into the reduced section 32 of the perforation through which it extends, the cutting edges 38-38 readily penetrate the insulation and are finally brought up into tight gripping engagement with the wire itself.

Initially the plate member 26 is disposed with the

widened end sections 30 of its perforations in alignment with the channels 12 and 16 of the block. Thereafter the plate member is shifted or moved in its plane so as to bring the narrowed end sections 32 into alignment with the channels. Movement of the plate member from the first position to the second position will cause the narrowed end sections 32 of the perforations to cut through the insulating covering surrounding the wires and come into direct contact with the wires. The early movement of the plate member from the first position to the second position is resisted by the compression and dislodgment of the covering material acted upon by the side walls 34-34, but after this material has been forced into the widened end section 30 the final movement of the plate member is effected with less effort. The operation may be characterized as being similar to a snap action, the member's initial movement being resisted but its final movement being comparatively free and easy. The dislodged insulating material, such as indicated at 36 in Fig. 6, spreads laterally into the widened end sections 30 of the perforations and functions to releasably lock the plate member against retractile movement.

Although the plate member 26 may be shifted from its initial position to its final position by a rotary motion around a centrally disposed axis in the housing, it is preferred to accomplish this change in position by a straight-line movement. This facilitates the application of force for moving the member and in addition provides a sealing enclosure for the member in its final position as hereinafter described.

The plate member 26 is actuated from the first position to the second position from the outside of the housing or block 10. To this end, the cavity 28 in the block opens out through one side edge thereof and the plate member is provided with a longitudinal dimension such that even when fully inserted into the cavity one end section thereof projects through this opening and beyond the side edge. The projecting portion of the plate member 26 constitutes an operating extension 40 for actuating the plate member from the first position to the second position. Carried on the outer end of the extension 40 of the plate member is an insulating body 42 which may be formed of the same material as the block 10 and rectangularly shaped as shown so that surface portions of the body and the block 10 extend flush with one another. The insulating body 40 serves as a handle against which either the hands of the operator or a tool may be applied to move the plate member. The insulating body 42 is so positioned on the extension 40 of the plate member that in the initial position of the plate member it is spaced from the adjacent edge of the block but in the final position of the plate member it is brought up into abutment with the side edge to completely surround the plate member insulated material and to form a substantially moisture-proof seal.

The initial operating position of the plate member 26 is shown in Figs. 3 and 4. The final operating position of the plate member is shown in Figs. 1, 2 and 5.

In the initial position of the plate member, any desired number of insulated wires such as indicated at 20 and 24 are inserted into the channels of the block. Depending on the use of the device, one of these wires as indicated at 24 may be passed completely through the channel 18 so as to project from opposite sides of the block. Thereafter the plate member is moved to its final position by application of finger pressure or a tool to the insulated body 42 on the projecting end of the plate member. Usually it will be found more convenient to use a tool, such as a pair of pliers, for forcing the plate member to its final position. For this purpose, the pair of jaws is arranged to straddle the block with one jaw bearing against the insulated knob on the plate member and the other jaw bearing against the opposite end of the block. In the final closed position of the plate member, the side walls 34-34 of each narrowed end section

of the plate apertures are brought up into direct contact with the wires as shown in Figs. 6 and 8. The wires are thus electrically connected together through the plate member and firmly locked within the block.

The modification of Figs. 9 and 10 is similar to the embodiment of the invention previously described except that the block 44, corresponding to block 10, is longer and wider and provided with more wire receiving holes or channels 46 than formed in block 10. Moreover, in the modification, all of the channels are shown in Fig. 10 as terminating in closed ends short of the bottom side of the block whereas in the previously described embodiment of the invention at least one of the channels opens out through opposite sides of the block. The modification is completed with the provision of a plate member 48 corresponding to plate 26 and having an insulating body 50 on its projecting end corresponding to the body 42. Figs. 9 and 10 show the plate member in its final position, gripping and electrically contacting insulated wires received in the channels 46.

What I claim is:

1. A connector for a plurality of insulated wires comprising a housing of insulating material formed to provide openings to receive said wires in spaced apart relation, a perforated plate of electrically conductive material, a channel in said housing for slidably receiving and guiding said plate, each said opening extending through a housing wall at one side and into the wall at the other side of said channel, said plate perforations each being provided with a widened end section sufficient to receive and pass the respective wire with insulation intact, a narrowed perforation extension extending in substantially the same direction from each said plate perforation widened end section of such width as to receive only the bare wire and insure metal deformation to grip said wire and to provide electrical contact between said plate and wire, said plate being slidable from a wire receiving position with said widened end sections aligned with said openings to a wire electrical contact and connecting position with said narrowed perforation end extensions aligned with said openings, the insulation being substantially simultaneously stripped from the sides of said wires and metal deformed for electrical contact between said plate and wires by movement of said plate.

2. A connector for a plurality of insulated wires comprising a housing of insulating material formed to provide openings to receive said wires in spaced apart relation, a perforated plate of electrically conductive material, a channel in said housing for slidably receiving and guiding said perforated plate, each said opening extended through a housing wall at one side and into the wall at the other side of said channel, said plate perforations each provided with a widened end section sufficient to

receive and pass the respective wire with insulation intact, a narrowed perforation extension extending in substantially the same direction from each said plate perforation widened end section of such width as to receive only the bare wire and insure metal deformation to grip said wire and to provide electrical contact between said plate and wire, a perforated plate wire receiving position with said perforation widened end sections aligned with said openings, a wire electrical contact and connecting perforated plate position with said narrowed perforation extensions aligned with said openings, dislodged insulating material being stripped from said wires resiliently spread into and confined within said perforation widened end sections and between said housing channel walls restraining said electrical conductive perforated plate against retractable movement from said wire electrical contact and connecting position.

3. In the connector defined in claim 2 opposite side walls of said plate perforation narrowed extensions arranged in slightly diverging relationship opening toward said widened ends and said opposite side walls of said narrowed perforation extension inclined or beveled to provide cutting or slicing edges.

4. In the connector defined in claim 2 at least one of said wire openings in said housing and the said insulated wires inserted therein extending completely through said housing.

5. In the connector defined in claim 2 said plate projecting outward from said channel, an insulating body mounted on the projecting end of said plate and spaced from said housing when said plate is in said wire receiving position, said insulating body abutting said housing when said plate is in said wire electrical contact and connecting position.

6. In the connector defined in claim 2 a connector in which electrically conductive members are wholly enclosed within insulating material when said plate is in said wire electrical contact and connecting position.

7. In the connector defined in claim 2 a connector in which it is safe to electrically contact and connect said wires even though a wire may be electrically charged.
